Patented June 8, 1915
2 SHEETS—SHEET 2.

UNITED STATES PATENT OFFICE.

WILLIAM WOODWARD, OF CHICAGO, ILLINOIS.

INTERNAL-COMBUSTION ENGINE.

1,142,074.

Specification of Letters Patent.

Patented June 8, 1915.

Application filed March 19, 1914. Serial No. 895,770.

To all whom it may concern:

Be it known that I, WILLIAM WOODWARD, a citizen of the United States, and a resident of the city of Chicago, county of Cook, and State of Illinois, have invented certain new and useful Improvements in Internal-Combustion Engines, of which the following is a specification.

My invention relates to improvements in internal combustion engines, and has for its object the provision of an improved engine of this character provided with an improved valve and valve operating arrangement which is of simple and economical construction and highly efficient in use.

The invention consists in the combinations and arrangements of parts hereinafter described and claimed.

The invention will be best understood by reference to the accompanying drawings forming a part of this specification, and in which,

Figure 1 is a sectional view taken through the crank case of an engine embodying my invention, showing the cylinder partially in section, Fig. 2, a section taken on line 2—2 of Fig. 1, Fig. 3, a section taken on the plane indicated by the lines 3—3 of Figs. 1 and 2, Fig. 4, an enlarged section taken on line 4—4 of Fig. 3, and Fig. 5, a perspective view of one of the valves employed in the construction.

The preferred form of construction as illustrated in the drawings comprises a crank case 6 which may be of any usual or desired construction. A cylinder 7 is secured to crank case 6 in any usual or desired manner and is provided with intake and exhaust ports 8 and 9 respectively. Cylinder 7 is provided with a cylinder head 10 having a spark plug 11 therein. The ports 8 and 9 are arranged diametrically from each other and longitudinal ribs or bosses 12 are arranged on the exterior wall of cylinder 7 diametrically opposite each other and in a plane at right angles to the diametric plane corresponding to ports 8 and 9. Each of the bosses 12 is provided with a longitudinal passage 13 having a lateral extension 14 at

its upper end communicating with the upper 50 portion of cylinder 7. A valve operating stem 15 is slidably and rotatably mounted in each of the passages 13 and is provided at its upper end with an inwardly extending angular arm 16 projecting into cylinder 7 55 and loosely engaging a socket 17 in a boss 18 formed on the inner upper central portion of a valve-shoe 19, as indicated. Each of the valve-shoes 19 is ground to fit nicely the portion of the interior wall of cylinder 7 60 immediately surrounding the corresponding ports 8 and 9, and each of said valves is provided with a port 20 adapted to register with the corresponding ports 8 and 9 as said valve is reciprocated on the inner wall of 65 cylinder 7. By this arrangement it will be observed that each of the valves 19 is entirely free to seek its seat against the interior wall of cylinder 7 and at the time of compression or expansion in said cylinder 70 will be held tightly to its seat by the pressure in the cylinder thus effecting a tight seal when a tight seal is essential. At its lower end each of the passages 13 is enlarged and a packing 21 is arranged in the 75 upper portion of each of said enlargements. A head 22 is loosely mounted on each of the stems 15 in the corresponding passage enlargement, and is provided with a lug or feather 23 sliding in a groove 24 formed in 80 the wall of the corresponding enlargement, thus effecting a splined connection between said head and said enlarged passage, or in other words, a connection which permits of longitudinal movement of said head in said 85 enlargement, and prevents rotation thereof. A helical spring 25 is arranged on the protruding end of each of the stems 15 and has its upper end secured to the corresponding head 22 and its lower end secured to another 90 head 23 which is fixed to the lower end of said stem. Before the parts are assembled, torsional tension is placed in each of the springs 25 by rotating the corresponding heads 22 and 23 relatively to each other, and 95 in a direction to cause such torsional tension to tend to hold the corresponding valve 19 yieldingly to its seat against the inner wall.

of cylinder 7, as will be readily understood. By this arrangement all that is necessary to do in order to remove valves 19 for regrinding or other repairs, is to remove cylinder 5 head 10 and then turn arms 16 outwardly against the resistance of springs 25 which will release the valves and permit their removal. This constitutes a simple and efficient means for holding the valves in position and for controlling the same.

Each of the heads 26 is normally held in contact with an arm 27 of a corresponding bell crank lever, the other arm 28 of which runs upon the periphery of a corresponding 15 cam 29 fixed to the cam shaft 30 of the engine, the engine illustrated being of the four-cycle type. Each of the cams 29 is provided with an outer peripheral cylindrical land 31, of comparatively great extent occupying nearly 180 degrees of the periphery, and an inner land 32 occupying a comparatively small portion of the periphery of the cam, the remaining portions of the periphery of said cam being composed of surfaces 20 connecting said lands. This constitutes a simple and efficient form of cam for the purpose and one which operates at high speed 25 without noise.

The cam shaft 30 is driven from crank 30 shaft 33 which is mounted in crank case 6 in any usual or desired manner. Crank shaft 30 is provided with the usual crank 34 connected by means of a connecting rod 35 with the usual piston 36 operating in cylinder 7.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the 45 appended claims.

Having described my invention what I claim as new and desire to secure by Letters Patent is:

1. An internal combustion engine comprising a cylinder having inlet and exhaust ports in the walls thereof; separate inlet and exhaust valves sliding against the inner walls of said cylinder for controlling said ports; springs arranged to press said valves 50 to their seats; and means for operating said valves, substantially as described.

2. An internal combustion engine comprising a cylinder having a port and a passage in the walls thereof; a valve in said cylinder for controlling said port; a slideable and rotatable stem provided with an arm 55 extending through said passage into said cylinder and operatively engaging said valve; a spring arranged to tend to rotate

said stem to press said valve to its seat; and 65 means for reciprocating said stem to operate said valve, substantially as described.

3. An internal combustion engine comprising a cylinder having a port in the wall thereof and a longitudinal passage communicating at one end with said cylinder; a valve in said cylinder for controlling said port; a stem rotatable and slideable in said passage and provided with an arm projecting into said cylinder and operatively engaging 70 said valve; a spring arranged to tend to rotate said stem to press said valve to its seat; and means for reciprocating said stem to operate said valve, substantially as described.

4. An internal combustion engine comprising a cylinder having ports in the walls thereof and longitudinal passages communicating at one end with said cylinder; valves in said cylinder for controlling said ports; 85 stems rotatable and slideable in said passages and provided with arms projecting into said cylinder and operatively engaging said valves; springs arranged to tend to rotate said stems to press said valves to their seats; 90 and means for reciprocating said stems to operate said valves, substantially as described.

5. An internal combustion engine comprising a cylinder having a port in the wall 95 thereof and a longitudinal passage communicating at one end with said cylinder; a valve in said cylinder for controlling said port; a stem rotatable and slideable in said passage and provided with an arm projecting 100 into said cylinder and operatively engaging said valve; a spring arranged to tend to rotate said stem to press said valve to its seat; means for reciprocating said stem to operate said valve; and a packing arranged 105 to seal said passage against leakage, substantially as described.

6. An internal combustion engine comprising a cylinder having ports in the walls thereof and longitudinal passages communicating at one end with said cylinder; valves in said cylinder for controlling said ports; stems rotatable and slideable in said passages and provided with arms projecting into said cylinder and operatively engaging said 110 valves; springs arranged to tend to rotate said stems to press said valves to their seats; means for reciprocating said stems to operate said valves; and packings arranged to seal said passages against leakage, substantially 115 as described.

7. An internal combustion engine comprising a cylinder having a port in the wall thereof and a longitudinal passage communicating at one end with said cylinder; a valve 125 in said cylinder for controlling said port; a stem rotatable and slideable in said passage and provided with an arm projecting into

said cylinder and operatively engaging said valve; a head loosely mounted on said stem and splined in said passage; a packing imprisoned in said passage by said head; a helical spring on said stem having one end secured to said head; a head fixed to said stem and secured to the other end of said spring; and means for reciprocating said stem to operate said valve, substantially as described.

8. An internal combustion engine comprising a cylinder having ports in the wall thereof and longitudinal passages communicating at one end with said cylinder; valves in said cylinder for controlling said ports; stems rotatable and slideable in said passages and provided with arms projecting into said cylinder and operatively engaging said valves; heads loosely mounted on said stems and splined in said passages; packings imprisoned in said passages by said heads; helical springs on said stems having one end secured to the corresponding head; a head fixed to each of said stems and secured to the other end of the corresponding spring; and means for reciprocating said stems to operate said valves, substantially as described.

9. An internal combustion engine comprising a cylinder having a port in the wall thereof and a longitudinal passage communicating at one end with said cylinder; a valve in said cylinder having a port arranged to register with and control said cylinder port; a stem rotatable and slideable in said passage and provided with an arm projecting into said cylinder and operatively engaging said valve; a head loosely mounted on said stem and splined in said passage; a packing imprisoned in said passage by said head; a helical spring on said stem having one end secured to said head; a head fixed to said stem and secured to the other end of said spring; and means for reciprocating said stem to operate said valve, substantially as described.

10. An internal combustion engine comprising a cylinder having ports in the wall thereof and longitudinal passages communicating at one end with said cylinder; valves in said cylinder having ports arranged to register with and control said cylinder ports; stems rotatable and slideable in said passages and provided with arms projecting into said cylinder and operatively engaging said valves; heads loosely mounted on said stems and splined in said passages; packings imprisoned in said passage by said heads; helical springs on said stems having one end secured to the corresponding head; a head fixed to each of said stems and secured to the other end of the corresponding spring; and means for reciprocating said

stems to operate said valves, substantially as described.

11. An internal combustion engine comprising a cylinder having a port in the wall thereof and a longitudinal passage communicating at one end with said cylinder; a valve in said cylinder for controlling said port; a stem rotatable and slideable in said passage and provided with an arm projecting into said cylinder and operatively engaging said valve; a head loosely mounted on said stem and splined in said passage; a packing imprisoned in said passage by said head; a helical spring on said stem having one end secured to said head; a head fixed to said stem and secured to the other end of said spring; and a cam for reciprocating said stem to operate said valve, substantially as described.

12. An internal combustion engine comprising a cylinder having ports in the wall thereof and longitudinal passages communicating at one end with said cylinder; valves in said cylinder for controlling said ports; stems rotatable and slideable in said passages and provided with arms projecting into said cylinder and operatively engaging said valves; heads loosely mounted on said stems and splined in said passages; packings imprisoned in said passages by said heads; helical springs on said stems having one end secured to the corresponding head; a head fixed to each of said stems and secured to the other end of the corresponding spring; and cams for reciprocating said stems to operate said valves, substantially as described.

13. An internal combustion engine comprising a cylinder having a port in the wall thereof and a longitudinal passage communicating at one end with said cylinder; a valve in said cylinder having a port arranged to register with and control said cylinder port; a stem rotatable and slideable in said passage and provided with an arm projecting into said cylinder and operatively engaging said valve; a head loosely mounted on said stem and splined in said passage; a packing imprisoned in said passage by said head; a helical spring on said stem having one end secured to said head; a head fixed to said stem and secured to the other end of said spring; and a cam for reciprocating said stem to operate said valve, substantially as described.

14. An internal combustion engine comprising a cylinder having ports in the wall thereof and longitudinal passages communicating at one end with said cylinder; valves in said cylinder having ports arranged to register with and control said cylinder ports; stems rotatable and slideable in said passages and provided with arms pro-

jecting into said cylinder and operatively engaging said valves; heads loosely mounted on said stems and splined in said passages; packings imprisoned in said passages by said heads; helical springs on said stems having one end secured to the corresponding head; a head fixed to each of said stems and secured to the other end of the corresponding spring; and cams for reciprocating

ing said stems to operate said valves, substantially as described.

In testimony whereof I have signed my name to this specification in the presence of two subscribing witnesses.
